BAG CLAMP

Charles Edwin Anderson, Narberth, Pa., assignor
of one-half to William H. Jefferies, Moylan,
Pa.

Application December 9, 1941, Serial No. 422,227

18 Claims. (Cl. 24—30.5)

My invention relates to clamps for the otherwise open ends of bags to prevent loss or interference with the contents of the bags except with injury to the bags which will disclose the fact of interference.

One purpose of the invention is to slide longitudinally inter-locking straps or bars, one upon the other, to a final holding position.

A further purpose is to slide longitudinally interlocking straps or bars, one upon the other, latching them together in final fastening position so as to require more pressure to overcome the resistance, to release the latch and open the clamp than is likely to be applied in normal operation.

A further purpose is to hold one end each of two slideable and separable straps together while permitting sliding clamping and release movement by head and slot connection and slidably inter-lock the other ends by a slot and pin connection.

A further purpose is to secure two separable sliding strap members of a clamp together by sliding longitudinal engagement and to use a lock in one of them to prevent sliding release movement between the parts.

Further purposes will appear in the specifications and in the claims.

I have preferred to illustrate a single form only, using a form which is practical, effective, reliable and inexpensive and which at the same time well illustrates the principles of the invention.

Figures 1 and 2 are perspective views of one form of my clamp showing the straps in different positions of relative longitudinal movement of the parts.

Figure 3 is a fragmentary top plan view of one end of a clamp showing the parts in released position.

Figure 4 is a fragmentary vertical longitudinal section of the structure of Figure 3 taken upon line 4—4 and showing parts at the end released.

Figure 5 is a view identical with Figure 4 except that parts at the end shown as in released position in Figure 4 are shown in closed position in Figure 5.

Figure 6 is a fragmentary top plan view of the ends of two clamp straps showing a modified form of clamp.

Figure 7 is a section of Figure 6 taken upon line 7—7.

Figure 8 is a perspective of a closed bag having the folded top of the bag within the clamp.

Figure 9 is a side elevation of the structure of Figures 1 and 2 showing two positions.

Figure 10 is a fragmentary enlargement corresponding to Figure 9 in closed position.

In the drawing similar numerals indicate like parts.

5 I am using the words bight, bighting, etc., in a special sense, referring to an impingement of the shoulders against the surface of the adjoining strap 11 at such an angle that the "bighting" edge tends to grip the surface and hold against 10 sliding movement along strap 11. The notches setting off the head are amply wide (lengthwise of the strap) to permit sliding and there is no engagement of the wings of the T-head with the strap 11 during the "bighting" impingement of the shoulders. This appears in Figure 10.

Bags of course require fastening of their folded open ends after filling. Usually cords or pins, or cords and pins are used but metal clamps are better and can be applied quickly and released 20 instantly. In many dye plants the folded end of the bag is tied in a knot, requiring an excessive bag length for the knot. My invention is suitable generally for temporary closure and has been found very useful, for example, for the bags 25 within which stockings are held while being dyed and by which as containers they are handled subsequent to the dyeing operation.

In the case of the stockings, much injury is done at the present time to the stockings through 30 the use of pins of the general blanket pin type which must pierce the fabric of the bag near the mouth and sometimes also pierce the stockings. The value of Nylon stockings is greater than the value of silk stockings and the loss from piercing 35 the stockings is therefore increased where the stockings are of Nylon and the percentage of stockings made from Nylon is increasing: with the result that the selection of a proper clamp to close the mouth of the bag, always material, 40 is now much increasing in importance.

The present invention is intended not only to close the top of the bag without impaling the bag nor any of its contents but affords a convenient means of locking the parts of the clamp 45 against release movement.

The clamp illustrated comprises two longitudinally slideable bars or straps which are secured to each other at adjacent ends so as not to interfere with relative longitudinal movement of 50 the straps and which have co-operating slot engagements, the connection at the left end in the figure producing a pivot, separable and movable longitudinally without losing the pivot. I provide a slot and pin spring-engaged co-operating 55 connection at the other end. The two bars or

straps 10 and 11 are relatively bowed between to leave room for them to grip on opposite sides against the folded fabric of a bag 12, adjacent to the open end of the bag.

The straps or bars 10 and 11 are used together and are bowed to surround the folded fabric of the bag. One of the straps, such as strap 11 can be the same for all forms within a considerable range of bag size and different straps 10 can be used with it, bearing different identifying data as to stocking size, for example.

Assuming that the strap 11 is to form the base upon which strap 10 pivots and slides, the strap 11 terminates in a closed slot 13 at the left in the figures and the strap 10 is notched at its left end at 14 so as to provide a head 15 which, when the strap 10 has been turned a quarter turn, as compared with Figure 8, can be passed through the slot and turned to the position indicated in Figure 8 to join the straps or, subsequently can be turned when they are to be separated. In the positions of the various figures the neck 16 can be slid longitudinally within the closed slot, providing movable pivotal connection between the straps. The head 15 in released position is free to engage against the under side 17 of the convex outer surface of strap 11 at the closed slot, holding the parts at the opposite sides of slot 13, against detachment at that end of the clamp, that is, at the left end, as shown in Figure 8, of its gripping engagement with a folded bag.

The two straps enclose a larger cross sectional space in their closed but not latched position (see dotted lines in Figure 9) than in their latched position (seen in full lines in Figure 9).

At the opposite right side of the bag in Figure 8 the opposite and otherwise free ends of the two straps slope relatively, forwardly and toward each other at 18 and 19 so as to provide a rearwardly flared space at 20 permitting pinching of the central parts of the straps at 21 and 22 toward each other, partly or fully closing the angular space 20 between them.

The end of the strap 10 is slotted lengthwise at 23 and is open at the end of the slot and of the strap at 24 so as to pass beneath the head 25 of a pin 26 rigidly secured in the end 27 of the strap 11.

With the closed slot end of strap 11 and the neck of strap 10 together the open slot end of 10 will not pass under the head of the pin in strap 11 without pressure of the two straps bodily toward each other, springing the straps somewhat together and taking up part of the space at 20 provided between the straps by the slope at 18 and 19 of the surface of the strap 10 at the slot with respect to the adjoining surface of strap 11.

The slope, causing convergence toward the ends of the straps, is reduced as a result of the spring of the metal as the slotted portion slides under the head of the pin.

When the pressure upon straps toward each other is removed (the pin and open slot being in latched or clamp-closed position or nearly that position) there remains a resilient pressure of the open-slot wall against the under side of the head of the pin and a resultant resilient pressure of the opposite ends of the straps, (the closed slot and T-head ends) against each other causing the shoulders back of the T-head to bear against the concave (inner) wall of the strap 11 at opposite sides of the closed slot.

Another use made of the continuing resilient

pressure between the walls of the open slot and the under face of the pin, while still maintaining spring pressure between the parts lengthwise of the pin is to provide the spring to make effective

5 a rest or dwell 30 into which the head 25 is snapped when the open slot has been pressed "home" lengthwise fully against the pin. This rest is provided by slightly recessing the metal at 31 and the metal of the straps has to be 10 sprung transversely together somewhat to permit the slot at the end of strap 10 to travel the length of the slot, to a point where the head fits into the rest or seat about the inner end of the slot. The spring of the straps toward each other 15 also in closed position presses the T-head away from the convex surface about the closed slot.

As a result of the "snap" of the parts in the final position, the straps are additionally restrained against relative longitudinal movement 20 until the middle parts of the two straps are sprung slightly toward each other preliminary to moving the one strap 10 longitudinally along the other in release. Coincidentally the shoulders adjacent the T-head are withdrawn from binding 25 engagement against the concave faces of the side walls about the closed slot.

In the main illustration the sides 28 and 29 of the open-ended slot 23 are chamfered so as to flare away from the strap 10 and the under side 30 of the head of the pin is similarly tapered to flare upwardly toward the head.

In Figures 6 and 7 the slot 23' is not chamfered along its edges but is parallel-edged to fit under a straight-shanked head. The head drops 35 into a slight countersink 30' when the head and the countersunk portion of the slot register.

In all forms the ends of the straps approach each other at 18 and 19 at a slight angle 32, giving this much angular room for the spring 40 bending of one strap toward the other while the head and slot are being moved relatively lengthwise of the slot during closing or release of the clamp.

When the straps have been fully closed, the 45 position seen in Figure 8, they may be locked against relative movement by insertion of the shackle 33 of a padlock within the outer end of the closed slot.

One or both of the straps is or are provided 50 with edge prongs or other engaging devices which are shown at 34 in the figures. Their purpose is to roughen the edge so as to engage the fabric of the bag and to prevent the fabric from being pulled through the clamp. The prongs are "one-way" engaging devices, i. e. prongs on one edge prevent movement of the fabric toward the edge of the particular strap and the prongs on the other edge retain the fabric against movement toward the other edge of the strap.

In the illustration the prongs are triangular and are stamped from the outside edges of the straps, the side lines of the prongs being cut free but the base lines of the prongs remaining in the straps.

During the stamping operation the prongs can be relatively sharpened by slightly forging the ends of the prongs so as to make them thinner and relatively sharper, sharpening the ends of the prongs so as to make them hold well against the fabric, preferably without piercing beyond the thickness of the fabric.

Where the prongs are not sharpened, of course, the prongs are merely bent downward about the base lines of the prongs as approximate pivots and the end of each prong which was formerly in

the side wall of the strap then extends at right angles to the direction of the length of the prong in the particular position to which the end of the prong has been swung.

Each of the straps is roughened to give the finger or thumb of the operator a good grip upon it so that less effort need be used relatively to move the straps. This is shown in serrations 35 and is particularly helpful where soap is present.

It will be evident that the concave curvature of the inner surface of strap 11, where the shoulders of strap 10 engage, facilitates release of the hold at the left end of the one strap upon the other when the head is pulled to the left at the same time that the bowed central part of strap 10 is pulled toward the left.

When the one strap is moved lengthwise of the other to set the clamp the enclosed fabric is compressed, as will be clear from Figure 9, and the resistance to compression of the fabric provides a resilient reaction tending to release the clamp and also tending to press the prongs and the fabric together.

It will be evident that the longitudinal movement of the head of the one strap within the closed slot of the other performs many functions. It pivots the parts at that end of the fastener, and at the same time it permits longitudinal movement of the one strap with respect to the other without interfering with the pivotal connection.

The longitudinal movement reduces the space within the straps and thus progressively compresses the fabric. By the wedging of the open slot face walls beneath the head the shoulders adjacent the T-head bind against the concave face of the walls about the closed slot and on release the shoulders move along the inner curve of the slot wall to relieve this binding engagement and to permit opening more easily than otherwise would be the case. The end of the closed slot provides for locking of the parts against release by the shackle of the padlock.

It will be evident that the slot and pin ends of the two straps offer not only guidance and retention during the longitudinal movement of one of the straps with respect to the other but by the springing away from each other and the rest into which the pin head fits in final position they hold the parts closed against release until springing of the bowed parts of the straps toward each other releases the transverse spring pressure opposing movement.

In operation, the fact that the material of the bag is and must be considerably compressed to hold it against being slid out from between the straps results in a reaction resilient pressure of the folded bag material tending to force one strap directly away from the other.

This reaction expansion of the bag material would have a tendency to press the outer edges 36 of the under sides of the wings 31 of the T-head against the outer convex surfaces 38 of the side frames 39 of the closed slot, freeing both inside and outside edges 40 and 41 of shoulders 42, adjacent the T-head from engagement with the concave inner faces 43 of the frame 39. However, the pressure of the under surface of the head 25 upon the inner end of the open slot at the "rest" forces bar 10 toward bar 11 in spite of the reaction pressure of the compressed bag material.

As a result the inner edges 40 engage with the inside faces 43 of the side frames, bighting against the interior faces of the two side frames.

This offers considerable resistance to opening movement. I emphasize it by forming grooves or recesses 44 across the inner surfaces of the frames, into which grooves these inner edges of the shoulders fit.

In order to release the clamp most easily, in the best form of my invention the middle parts of the two clamp straps are pressed toward each other in order to relieve the pressure holding 10 the head 25 within the rest or dwell at the inner end of the open slot, so as to relieve the hold this "rest" has upon the open slot end of clamp strap pin.

At the same time that the straps are sprung 15 generally toward each other, the T-head 15 is pushed transversely of the strap 11 to release the impingement of the shoulders and is pulled toward the left in Figure 8, lifting the shoulders away from or out of their bighting engagement with 20 the concave faces of the side frame. This is true whether the bight be accentuated by grooves in the side frames or not.

In this way the release is prepared for by a combination of springing the straps toward each 25 other at the middle or near the open slot end and forcing them away from each other at the closed slot end. The roughening of the straps is very helpful in holding the clamp for the pinching action at the open slot end also for friction 30 when sliding the straps with respect to each other after the rest engagement and the bight have been relieved.

It will be evident that the tendency of the straps to spring away from each other, restrained 35 at the open slot end by the under surface of the head of the pin, affords what might be termed a latch hold of the parts through the snapping of the head into a slight recess when the open slot and pin are relatively "home"; and that this may be made to assist the bight impingement in holding 40 the parts together, and may occur at the same position of the parts as the position at which the shoulders back of the T-head engage within the groove across the closed slot. However the bight 45 itself is fully effective to hold the clamp against movement even if no "rest" be provided and no groove.

The independent effectiveness of the means at 50 each end has been tested out by placing the groove slightly toward the closed end of the slot from the position at which the straps are "home", as shown, so that the strap may be shifted slightly 55 releasing the pin and rest engagement before the shoulders drop into the groove. Grooves may be used, in both positions lengthwise of the strap. This allows partial opening before the shoulders 60 will drop into the second groove and allows the retaining effect of the rest and head of pin, as one holding means and the shoulders and concave surface and/or groove as another holding means 65 to be appraised. Each proved to be effective alone without the use of the other and the use of the rest and head along with the groove give corresponding additional security.

In opening the clamp the straps are pressed together at the right hand end of the figures by squeezing them together at the middle and by concurrently pushing the T-head transversely to the strap 11 to separate the straps at the left hand end shifting the straps relatively while both holds 70 are thus released either by pushing on strap 10 lengthwise to the left or pulling upon the T-head to the left (against the closed end of slot 23) or both.

In view of my invention and disclosure varia-

tions and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention what I claim as new and desire to secure by Letters Patent is:

1. In a clamp for the open ends of bags a pair of bowed straps of resilient material having opening and closing movement with respect to each other generally lengthwise of the straps, and terminals upon the straps providing for head and slot pivotal connections at one end and pin and open end slot engagement between the other ends of the straps.

2. In a clamp for the open ends of bags, a pair of bowed straps of resilient sheet material having opening and closing movement with respect to each other generally lengthwise of the straps, a T-head and closed slot pivotal and longitudinally movable connection between the straps at one end and an overhanging pin and open end slot connection between the straps at their opposite ends.

3. In a clamp for the open ends of bags, a pair of bowed straps of resilient material having opening and closing movement with respect to each other generally lengthwise of the straps, a T-head and slot pivotal and longitudinally movable connection between the straps at one end, a headed pin and open end slot connecting the opposite ends, the bowing of the straps away from each other exerting a lateral pressure between the straps against the head of the pin at the inner end of the second slot in closed clamp position.

4. In a clamp for the open ends of bags, a pair of bowed straps of resilient material having opening and closing movement with respect to each other generally lengthwise of the straps, a T-head and closed slot pivotally movable connection between the straps at one end, a longitudinally movable connection at the opposite ends, and a padlock having its shackle passed through the first slot to prevent release movement of the T-head in this slot.

5. In a clamp for the open ends of bags, a pair of bowed straps of resilient material having opening and closing movement with respect to each other generally lengthwise of the straps, a T-head and slot pivotal longitudinally movable connection between the straps at one end and a headed pin and open end slot connecting the opposite ends, the second slot member having a dwell in which the head of a pin is held by resilience of the bowed straps away from each other when the clamp is in closed position.

6. In a clamp for the open ends of bags, a pair of bowed straps of resilient material having opening and closing movement with respect to each other generally lengthwise of the straps, a T-head and slot pivotally and longitudinally movable connection between the straps at one end, and a headed pin and end slot connecting the opposite ends, the strap at the first slot being concaved toward the other strap, whereby the T-head of the other strap is accessible along a convex opposite surface of the first strap to assist in releasing the clamp.

7. In a clamp for the open ends of bags, a pair of bowed straps of resilient material having opening and closing movement with respect to each other generally lengthwise of the straps, a T-head

and slot pivotally and longitudinally movable connection between the straps at one end, and headed pin and end slot connecting the opposite ends, the strap at the first slot being concaved toward the other strap, whereby the T-head of the other strap is accessible along the convex opposite surface of the first strap to assist in releasing the fastener, and the spring of the bowed straps tighten walls of the second slot against the under surface of the pin.

8. In a clamp for the open ends of bags, a pair of bowed straps of resilient material whose concave surfaces face each other having opening and closing movement with respect to each other generally lengthwise of the straps, slot and pin fastenings for the straps, at one end forcing the other ends of the straps toward each other and causing pressure contact between them, at which other end sliding engagement takes place.

15 9. In a clamp for the open ends of bags, a pair of bowed straps of resilient material having opening and closing movement with respect to each other generally lengthwise of the straps, and terminals upon the straps providing head and slot

25 pivotal connections at one end and pin and open end slot engagement between the other ends of the straps and engaging prongs carried by the straps and pressed into contact with the material of the bag, extending perpendicular to the direction of the relative movement of the straps.

30 10. In a clamp for the open ends of bags, a pair of bowed straps of resilient material having opening and closing movement with respect to each other generally lengthwise of the straps, a T-head and slot pivotally movable connection between the straps at one end, and a slot connection at the opposite ends, prongs extending inwardly from the one strap toward the other in planes perpendicular to the path of relative longitudinal movement of the straps to engage the bag material against lengthwise bag movement while permitting sliding movement of one strap with respect to the other in fastening and release sliding movement.

35 45 11. A clamp comprising opposed oppositely bowed straps having each a slot and a member extending into the slot of the other, in open position pivoting one upon the other and having a smaller cross section of space between the straps in fully closed position than in partially closed position.

50 12. In a clamp, a pair of bowed straps having respectively at one end, one strap longitudinally slotted and the other necked to provide a head

55 and adjacent shoulders, and at the second end longitudinally movable engaging faces, the straps being sloped toward each other at this second end and, when engaged, pressing the straps toward each other, to cause the shoulders at the first end to bight into the facing surface of the strap about the adjacent slot.

60 13. In a clamp, a pair of bowed straps comprising, respectively, one strap having a closed slot in the one end and a headed pin on the concave side of the strap at the other end and the other strap necked to provide a head capable of passing through the closed slot and shoulders to bight against the side about the closed slot on the concave side of the strap, and at the other end an open ended slot adapted to be sprung under the head of the pin, whereby the springing of the strap to locate the slot walls under the head of the pin causes bighting of the shoulders.

65 70 14. In a clamp, a pair of bowed straps comprising, respectively, one strap having a closed slot

in the one end and a headed pin on the concave side of the strap and the other strap necked to provide a head capable of passing through the closed slot and shoulders to bight against the sides of the closed slot on the concave side of the strap and at the other end an open ended slot adapted to be sprung under the head of the pin whereby the springing of the strap to pass its end under the head of the pin causes bighting of the shoulder, the face of the concave side of the closed slot being grooved to accentuate the bight and the head being accessible on the convex side of the slot to pull toward the outer end of the slot in order to disengage the bight.

15. In a clamp, a pair of facing bowed straps having each a longitudinal slot at one end and a head in position to enter the slot of the other strap, the slot in one strap being closed and the head of the second, cooperating with it having shoulders adjacent the head, the relation of the head on the first strap to the second strap slot being such that the bowed straps must be sprung toward each other to cause engagement of the head and slot, and whereby the shoulders on the second strap are forced by the springing of the straps toward each other to impinge upon the adjacent surface of the first strap at the slot to hold the parts against longitudinal movement.

16. In a clamp, a pair of facing bowed straps comprising one strap having a closed longitudinal slot at one end whose walls are concave toward the other strap and a headed pin directed toward the second strap at the opposite end and a second strap having a T-head at one end to pass through the closed slot, with shoulders adjacent the T-end to engage the concave surface, and at the other end of the second strap an open ended longitudinal slot and a dwell for the head of the pin when the parts are in home position, the relation of the straps being such that when the straps are in closed position they are sprung toward each other by the engagement of the head of the pin with the second strap, the first strap cooperating with the shoulders to hold the parts.

- 5   17. In a clamp, a pair of facing bowed straps comprising one strap having a closed longitudinal slot at one end whose walls are concave toward the other strap and a headed pin directed toward the second strap at the opposite end and a second strap having a T-head at one end to pass through the closed slot, with shoulders adjacent the T-end to engage the concave surface, and at the other end of the second strap an open ended longitudinal slot and a dwell for the head of the pin when the parts are in home position, the relation of the straps being such that when the straps are in closed position they are sprung toward each other by the engagement of the head of the pin with the second strap, the first strap cooperating with the shoulders to hold the parts, the hold being accentuated by a groove in the first strap and the accentuation taking place coincidentally with the fitting of the head of the pin into the dwell.
- 10   15   18. In a clamp, a pair of facing bowed straps comprising one strap having a closed longitudinal slot at one end whose walls are concave toward the other strap and a headed pin directed toward the second strap at the opposite end and the second strap having a T-head at one end to pass through the closed slot, with shoulders adjacent the T-end to engage the concave surface, and at the other end of the second strap an open ended longitudinal slot and a dwell for the head of the pin when the parts are in home position, the relation of the straps being such that when the straps are in closed position they are sprung toward each other by the engagement of the head of the pin with the second strap, the first strap cooperating with the shoulders to hold the parts, the hold being accentuated by a groove in the first strap and the accentuation taking place coincidentally with the fitting of the head of the pin into the dwell.
- 15   25   19. In a clamp, a pair of facing bowed straps comprising one strap having a closed longitudinal slot at one end whose walls are concave toward the other strap and a headed pin directed toward the second strap at the opposite end and the second strap having a T-head at one end to pass through the closed slot, with shoulders adjacent the T-end to engage the concave surface, and at the other end of the second strap an open ended longitudinal slot and a dwell for the head of the pin when the parts are in home position, the relation of the straps being such that when the straps are in closed position they are sprung toward each other by the engagement of the head of the pin with the second strap, the first strap cooperating with the shoulders to hold the parts, the hold being accentuated by a groove in the first strap and the accentuation taking place when the straps have been shifted partly toward opening position from the engagement of the head with the dwell.
- 20   30   20. In a clamp, a pair of facing bowed straps comprising one strap having a closed longitudinal slot at one end whose walls are concave toward the other strap and a headed pin directed toward the second strap at the opposite end and the second strap having a T-head at one end to pass through the closed slot, with shoulders adjacent the T-end to engage the concave surface, and at the other end of the second strap an open ended longitudinal slot and a dwell for the head of the pin when the parts are in home position, the relation of the straps being such that when the straps are in closed position they are sprung toward each other by the engagement of the head of the pin with the second strap, the first strap cooperating with the shoulders to hold the parts, the hold being accentuated by a groove in the first strap and the accentuation taking place when the straps have been shifted partly toward opening position from the engagement of the head with the dwell.
- 25   35   21. In a clamp, a pair of facing bowed straps comprising one strap having a closed longitudinal slot at one end whose walls are concave toward the other strap and a headed pin directed toward the second strap at the opposite end and the second strap having a T-head at one end to pass through the closed slot, with shoulders adjacent the T-end to engage the concave surface, and at the other end of the second strap an open ended longitudinal slot and a dwell for the head of the pin when the parts are in home position, the relation of the straps being such that when the straps are in closed position they are sprung toward each other by the engagement of the head of the pin with the second strap, the first strap cooperating with the shoulders to hold the parts, the hold being accentuated by a groove in the first strap and the accentuation taking place when the straps have been shifted partly toward opening position from the engagement of the head with the dwell.
- 30   40   22. In a clamp, a pair of facing bowed straps comprising one strap having a closed longitudinal slot at one end whose walls are concave toward the other strap and a headed pin directed toward the second strap at the opposite end and the second strap having a T-head at one end to pass through the closed slot, with shoulders adjacent the T-end to engage the concave surface, and at the other end of the second strap an open ended longitudinal slot and a dwell for the head of the pin when the parts are in home position, the relation of the straps being such that when the straps are in closed position they are sprung toward each other by the engagement of the head of the pin with the second strap, the first strap cooperating with the shoulders to hold the parts, the hold being accentuated by a groove in the first strap and the accentuation taking place when the straps have been shifted partly toward opening position from the engagement of the head with the dwell.

CHARLES EDWIN ANDERSON.
